UNITED STATES PATENT OFFICE.

CHESTER A. FRICK, OF MUNCIE, INDIANA, ASSIGNOR TO GLASCOCK BROTHERS MANUFACTURING COMPANY, OF MUNCIE, INDIANA, A CORPORATION OF INDIANA.

CORRUGATED-SHEET-BENDING MACHINE.

Application filed May 1, 1925. Serial No. 27,152.

My invention relates to improvements in sheet metal bending machines and has particular reference to a machine for bending previously corrugated sheets of metal.

5 One of the objects of my invention is to provide a machine which will bend a previously corrugated metal sheet longitudinally with the corrugations, to impart intermediate of the ends of the sheet, a substantially cylindrical formation to the sheet body leaving the end portions substantially straight and lying parallel with one another.

For the purpose of disclosing my invention I have illustrated one embodiment 15 thereof in the accompanying drawings, in which

Fig. 1 is a side elevation partly in section, of a machine embodying my invention, and

Fig. 2 is a plan view thereof, partly in 20 section.

In the embodiment illustrated I provide a base or backing member 1 which is adapted to extend substantially vertical from a support and is provided with a foot 2 by which 25 it is secured in position on its support. The front face of this base 1 is adapted to receive and support a transversely corrugated bed die 3 which is preferably hollow on its rear face and is provided with inturned lugs 30 4 by which it may be bolted to the base 1. Extending through the bearing 5 on the front face of the base 1, which bearing is formed in a suitable box integrally formed with the base, is a shaft 6 the ends of which 35 project beyond the top and bottom of the base 1. A U shaped yoke, the two legs 7 of which take over the ends of the shaft 6, carries a roller die 8 having its surface corrugated to co-operate with the corrugations 40 in the bed die 3. This roller is mounted on a shaft 9 journaled in pillow blocks 10 slidably mounted in the legs 7 of the yoke and held in their adjusted position by means of set screws 11. Suitable collars 12 are 45 secured to the opposite ends of the shafts to prevent lateral displacement of the shaft in the pillow blocks.

The side faces of the base 1 are corrugated and one has secured thereto a clamping plate 50 13 having its inner face corrugated to coincide with the corrugations of the side face of the base and this clamping plate 13 is held in clamped position by adjusting screws 14.

55 In operation the yoke and bending roll 8

are thrown to one side as indicated in dotted lines in Fig. 2. The previously corrugated sheet is then inserted in the clamp formed by the side face of the base 1 and the clamping member 13 and if its position has been determined by the gage member 15 the clamping plate 13 is set up until the plate is securely clamped in position. The roller 8 is then set by the adjusting screws 11, up against the plate and the yoke then swung to revolve the roller about the bed die 3, a suitable lever handle 16 on the yoke being provided for this purpose. As the roller revolves about the bed die 3, rotating on its own axis at the same time, the corrugated sheet is bent around the bed die until the roller has swung past the center of the bed die and in a position on the opposite side corresponding to the position shown in dotted lines in Fig. 2. The curvature in the corrugated plate is thus completed and while in the machine the straight ends of the plate are inclined past the parallel, or toward one another. When the plate is removed from the machine the tendency of the plate to spring back to its original form moves or straightens these sides out so that they lie substantially parallel.

To accommodate the roll 8 when it is swung into the position in dotted lines, the front face of the clamping plate 13 is corrugated as at 17 to coincide with the corrugations in the bed die 3.

I claim as my invention:

1. In a machine for bending corrugated sheets of metal, the combination with a sheet receiving bed substantially U shaped in cross section and of the same cross sectional dimension from end to end, the legs of the U being drawn inwardly at their extremities and forming substantially flat sides, the face of said bed having formed therein a plurality of transversely extending corrugations adapted to receive the corrugations of the sheet to be bent, a clamp for securing the sheet to be bent against one of the flat faces of the bed and adapted to hold the sheet against longitudinal movement and a roller having a series of parallel corrugations formed in its face to coincide with the corrugations formed in the bed and mounted to roll on the face of said bed beginning at a point on one of the side faces and ending at a point on the opposite side face and beyond the bight in the U.

2. In a machine for bending corrugated sheets of metal, the combination with a sheet receiving bed substantially U shaped in cross section and of the same cross sectional dimension from end to end, the legs of the U being drawn inwardly at their extremities and forming substantially flat sides, the face of said bed having formed therein a plurality of transversely extending corrugations 10 adapted to receive the corrugations of the sheet to be bent, a clamp for securing the sheet to be bent against one of the flat faces of the bed and adapted to hold the sheet against longitudinal movement, a roller having a series of parallel corrugations formed in its face to coincide with the corrugations formed in the bed and mounted to roll on the face of said bed beginning at a point on one of the side faces and ending at a point on the 15 opposite side face and beyond the bight in the U, and means for unyieldingly advancing the roller toward the bed.
3. In a machine for bending corrugated sheets of metal, the combination with a sheet receiving bed substantially U shaped in cross section and of the same cross sectional di-

mension from end to end, the legs of the U being drawn inwardly at their extremities and forming substantially flat sides, the face of said bed having formed therein a plurality of transversely extending corrugations adapted to receive the corrugations of the sheet to be bent, a clamp for securing the sheet to be bent against one of the flat faces of the bed and adapted to hold the sheet against longitudinal movement, a yoke pivoted on the axis of the bight of said U, a roller mounted in said yoke and having a series of circumferential peripheral corrugations coinciding with the corrugations on the face of said bed, said yoke permitting said roller to roll on the face of the bed from a point on one of the side faces of the bed to a point on the opposite side face of the bed, and means on said yoke for unyieldingly advancing the roller toward the bed.

In witness whereof I, CHESTER A. FRICK, have hereunto set my hand at Muncie, Indiana, this 28th day of April, A. D. one thousand nine hundred and twenty five.

CHESTER A. FRICK.
